O. F. FORSBERG

SWITCHING MECHANISM

Filed Feb. 6, 1923

FIG. 3.

FIG. 1.

Inventor:
Oscar F. Forsberg
by E.W. Adams
Atty.

UNITED STATES PATENT OFFICE.

OSCAR F. FORSBERG, OF YONKERS, NEW YORK, ASSIGNOR TO WESTERN ELECTRIC COMPANY, INCORPORATED, OF NEW YORK, N. Y., A CORPORATION OF NEW YORK.

SWITCHING MECHANISM.

Application filed February 6, 1923. Serial No. 617,242.

To all whom it may concern:

Be it known that I, OSCAR F. FORSBERG, a citizen of the United States of America, residing at Yonkers, in the county of West-
chester and State of New York, have invented certain new and useful Improvements in Switching Mechanisms, of which the following is a full, clear, concise, and exact description.

10 This invention relates to switching mechanisms and more particularly to the so-called coordinate switch of the type employed in automatic telephone exchanges.

In switches of the above mentioned character, operating cards are provided for sets of active contacts and by the conjoint operation of coordinately disposed bars, the cards are moved in such a manner as to carry the active contacts into engagement 20 with sets of passive or grid conductors thereby effecting telephonic connections between calling and called subscribers' lines associated with the switch contact sets.

In such a switch as is particularly disclosed in British Patent No. 183,438, issued to Western Electric Company, Limited, accepted September 6, 1923, it is desirable that the vertical operating bars be sectionalized, there being one section for each group of 30 sets of horizontal link or grid conductors and all the sections being rigidly coupled to form a single operating unit capable of actuation by a single operating means. To function efficiently, switches of this nature 35 must be quick operating and to obtain this desirable characteristic, the bearings provided for the rotatable members should be of such a nature as to reduce friction to a minimum. It is not unlikely that during 40 the shipping of such switches, the vertical operating members become bent or slightly bowed which results in considerable binding at the bearings of the vertical rods thereby increasing friction and retarding the movement of the vertical operating rods.

45 It is, therefore, an object of this invention to preclude the possibility of inefficient operation of the operating bars in a coordinate switch caused by the inaccurate alignment of the sections thereof.

This object is accomplished by providing the vertical operating rod sections with couplings having a pin and slot arrangement forming a universal joint. By the use of

the specific coupling disclosed herein, the vertical operating bars, though comprising rigid sections are practically flexible operating units.

The above and other objects of this invention will be readily discernible from the following detailed description and by reference to the accompanying drawing in which Fig. 1 shows the specific coupling to be covered in this application; Fig. 2 shows an improved top section of the vertical operating bars and its associated operating mechanism; Fig. 3 shows a fragmentary view of a coordinate switch embodying the features of this invention; Fig. 4 shows a portion of the switch structure disclosed in Fig. 3 pointing out the relative positions of the active and passive contacts and their respective operating bars, the horizontal operating bar being in its operated position.

Referring to Fig. 1, there is shown a bracing element 10 which forms a part of the switch structure shown in Fig. 3. A section 11 of a vertical operating bar is provided with a sleeve 12 rotatably mounted thereon and fitting a circular aperture in the member 10. The sleeve 12 acts as a bearing for the vertical section 11. Securely mounted on the end of the section 11 by a rivet or bolt 13 is a coupling sleeve 9 provided with two diagonally disposed slots 14 and 15 which extend in the direction of the axis of the sleeve for short lengths on the upper end of the sleeve. A cylindrical aperture 8 is centrally located in the lower end of the sleeve 9, through which the upper end of the section 11 extends. A cylindrical aperture 16 is centrally located in the upper end of the sleeve 9 and is of a larger diameter than the section 17 of the vertical operating bar into which the end of section 11 also extends. The section 17 is provided with a transverse cylindrical aperture which houses the main body portion of a pin member 18 which is provided with two projections fitting the slots 14 and 15 and serving to loosely key the section 17 to the sleeve 9. The lower end of the section 17 has a convex bearing surface and normally rests on the concave upper end of the section 11. A spring or latch member 20 has one end thereof secured to the sleeve 9 while the other end passes through one of the pro-

105

jections of the pin member 18 and serves to latch the section 17 to the section 11.

In the establishment of a telephonic connection as will hereinafter be described in detail, the upper bar 17 is rotated and through the medium of the extending portions of the pin 18, this movement is imparted to the sleeve 9 which in turn, being rigidly mounted on the section 11, causes this section to move in a like manner. The flexibility of the coupling is effected by virtue of the combined effects of the slots and pin arrangement, the clearance between the section 17 and the sleeve 9 and the respective convex and concave bearing surfaces of the sections 17 and 11. It is apparent from Fig. 1 that section 17 is free to move angularly through a limited distance relative to section 11. It will be understood that in switches wherein the vertical operating bars consist of more than two sections, the upper end of the section 17 will be a duplicate of the upper end of the section 11 and in like manner, the lower end of section 11 will correspond to the lower end of section 17.

Referring now to Fig. 2, there is shown the uppermost section of a vertical operating bar and its associated operating mechanism. This section comprises a tong or fork-shaped member 21 which cooperates with a coupling element 22 rigidly secured to the next succeeding section 17 of the vertical operating bar which is provided with a bearing 23 similar to the bearing 12 in Fig. 1. The coupling member 22 is provided with diagonal slots which cooperate with the extending portions of the tong or fork-shaped member 21 in effecting a universal coupling between the member 21 and the next succeeding section 17.

A contact mounting element 24, integral with the member 27, is provided for the contacts 26. The member 27 has securely mounted thereon a cup-shaped bushing 60. The circular wall of the bushing 60 acts as a housing for the upper end of the coil spring 32 and is provided with a slot 61 which admits the end of the spring, thereby effecting the tensioning of the spring when the electromagnet 31 is energized and the section 21 rotated. The bushing 60 insures a central location for the spring 32 with respect to the section 21.

The member 21 is provided with a projection 29 which cooperates with an arm 30 rigidly secured to the armature of the electromagnet 31 which is securely mounted on the framework of the switch. The energization of the magnet 31 causes the rotation of its associated section 21 through the medium of the cooperating elements 29 and 30. The upper end of the section 21 is provided with a lateral projection 40 which actuates the contacts 26 subsequent to the energization of the magnet 31. The restoring spring 32 is

provided to return the operating bar to normal subsequent to the deenergization of magnet 31.

To remove a vertical operating member from a coordinate switch of this type, the mounting element 27 and its associated contacts 26 are removed from the switch framework; the element 40 is then removed from the section 21; the bar is then drawn vertically, the coupling members 9 and their associated bearings 12 passing through the apertures in the bracing members 10 until the coupling member 22 clears the top of the switch frame. The coupling 22 is then removed from the next succeeding section and the remaining sections are again drawn vertically until the next coupling member 9 clears the top of the switch. This member is then removed in an obvious manner and the same procedure is continued until all of the sections have been removed. It will be noted that the bracing members 10 are provided with slots 35 which permit the passage of the camming fingers 36 therethrough during the removal of the vertical rod sections. Each vertical operating bar is provided with a step bearing 39, which comprises in general, a bolt and lock nut, the head of the bolt being provided with a projection which fits a cavity in the lower section of the operating bar. In this manner, the head of the bolt acts as a bearing for the bar and by manipulating the lock nut, the operating bar may be adjusted vertically.

The following description made with reference to Figs. 3 and 4 will give a clear understanding of the operation of a switch of this type.

Sets of grid or passive conductors 40, 41 and 42 are securely fastened at their ends to a fixed member (not shown) forming a part of the switch structure. A support 43 of insulating material also suitably secured to the frame of the switch is provided for each row of sets of flexible contact springs or active conductors 44, 45 and 46. The supports 43 may be of any suitable length and may carry any number of sets of contact springs depending on the switch capacity desired. The free ends of each set of contact springs 44, 45 and 46 extend through oblique apertures 47 in operating members or cards 48. In normal position, the card 48 holds the contact springs out of engagement with the passive conductors.

Coordinately disposed bars 49 and 50 are adapted to be rotated through small angles by the actuation of armatures 51 and 52, respectively, upon the energization of electromagnets 53 and 54, the armatures 51 and 52 being securely mounted on the operating bars 49 and 50, respectively.

The supporting member 43 also supports a flexible spring member 55, the free end of which extends through a circular aperture

in its associated card 48. Each vertical operating bar 49 is provided with a plurality of camming elements 36 which cooperate with an extending finger member 56 rigidly mounted on a horizontal operating bar 50 in effecting an engagement between a set of passive contacts 40, 41 and 42 and a set of active contacts 44, 45 and 46.

The operation of the switch is as follows: Assuming a subscriber desires to establish a connection, the removal of the receiver at the subscriber's station will cause the energization of a vertical line magnet 53 individual thereto. Magnet 53, upon energizing, attracts its armature 51 causing the rotation of an associated operating bar 49. The rotation of the bar 49 places the camming elements 36 in operable relation with their respective finger members 56. A horizontal link magnet 54 is then energized causing the rotation of a horizontal link bar 50. The rotation of the bar 50 causes the vertical movement of the finger member 56, the free end of which slides along the camming surface of the element 36 thereby causing the finger member 56 to engage the spring member 55 in its upward movement. The spring member 55 is thereupon moved vertically and carries with it, its associated operating card 48 and a corresponding set of active contacts 44, 45 and 46 until the active contacts engage a set of passive contacts 40, 41 and 42. By virtue of the oblique apertures 47 in the card 48, the active contacts are brought into engagement with the passive contacts with a wiping action. It is to be noted that the finger members 55 are provided with staggered projections forming a crotch which serves to hold the spring member 55 in engagement with the finger member 56 during the establishment of a connection.

It is apparent from the disclosure that the maintenance of a connection does not depend on the continued energization of magnets 53 and 54 but that the connection will be secured as long as the horizontal link magnet 54 remains energized irrespective of the energized condition of the vertical line magnet 53. In this manner, a vertical line magnet such as 53 that has cooperated with a horizontal magnet such as 54 is establishing a connection may become deenergized and cooperate with another horizontal link magnet such as 60 in the establishment of another connection. It will also be noted that the horizontal bar 50 in its operated condition holds the finger member 56 free

of the camming element 36 so that the member 56 is not disturbed upon the return of 60 the vertical line bar 49 to normal.

The vertical and horizontal line bars such as 49 and 50 are returned to normal subsequent to the deenergization of their respective magnets by restoring springs such as 32. 65

What is claimed is:

1. The combination in a switch structure having a plurality of sections, an operating member for each section, means for loosely joining said operating members to 70 form a self-adjustable single operating unit, and a plurality of members apertured for permitting the removal of the single operating unit in sections.

2. The combination in a switch structure 75 divided into sections, an operating member for each of said sections comprising a pin and a slotted sleeve for forming universal joints with its adjacent operating members, and a single means for operating said operating members as a unit, the aforesaid joints adapted to permit the removal of said members individually.

3. The combination in a switch structure 85 of coordinately disposed sets of contacts arranged in sections, means for operating said sets comprising intersecting bars, operating members on certain of said bars, one for each section, means for forming a loose coupling between said members to permit 90 self-adjustment for slight deformities in said members, said means comprising a sleeve which is fixedly mounted at one end of each of said operating members and which is provided at the other end with a boring of 95 a diameter larger than that of the adjacent operating member, and means for operating said intersecting bars to effect an engagement between said contact sets, the intersecting bar which comprises several of said operating members being arranged to operate as a single unit.

4. In a switching structure, contact sets, a sectionalized operating member therefor comprising a plurality of flexibly coupled 105 sections the uppermost section consisting of a tong-shaped member cooperating with a coupling normally associated with another section, and a lateral projection, and means cooperating with the lateral projection to 110 cause the operation of said operating member whereby engagement is effected between said contact sets.

In witness whereof, I hereunto subscribe my name this 2 day of February A. D., 1923

OSCAR F. FORSBERG.
